UNITED STATES PATENT OFFICE.

WILLIAM OSCAR YANCEY AND CHARLES CAROLUS DU MESNIL, OF CHICAGO, ILLINOIS.

HAT-PIN.

1,079,625.

Specification of Letters Patent. Patented Nov. 25, 1913.

Application filed April 17, 1912. Serial No. 691,541.

To all whom it may concern:

Be it known that we, WILLIAM O. YANCEY and CHARLES C. DU MESNIL, citizens of the United States, residing at Chicago, in the 5 county of Cook and State of Illinois, have invented certain new and useful Improvements in Hat-Pins, of which the following is a specification.

Our invention relates to devices for securing 10 women's hats in place on their heads, and has for its object the provision of a fastening means that will securely hold the hat in place to the exclusion of hat pins in ordinary use, and to prevent the hat from becoming 15 disfigured by the pin hole that results from the use of the ordinary stick pins employed.

Another object of our invention is the embodiment of a hat fastener of the class 20 described whereby the device may be quickly removed from one hat and replaced on another when desired by the wearer.

Our invention will be described in detail 25 hereinafter and illustrated in the accompanying drawings, in which,

Figure 1 is a bottom plan view of a hat, partly in section, showing our improved hat fastener in place; and Fig. 2, a cross section through the hat fastener.

In the drawings, similar reference characters will be used to designate corresponding parts throughout the several views.

A indicates a hat of any ordinary construction, having the crown B to which our 35 fastener is adapted to be secured.

The fastener is secured in place by means of brackets 1 and 2 having eyelets 3 and 4 respectively through which the brackets are sewed to the sides of the crown B, bracket 2 40 having inwardly extending arms 5 terminating in a loop 6 that acts as a journal for the shaft of the fastener to be hereinafter described. Bracket 1 is provided with a plate 7 having a laterally extending tubular casing 8 in which is mounted a coiled spring 9. The one terminal of the spring 9 is soldered or otherwise secured within the casing 8, while the other terminal of the spring projects exteriorly of the casing and is secured 45 in any desired manner to the shaft 10.

10 indicates a shaft journaled in loops 6 and in the casing 8, and having the other end of spring 9 secured thereto, the end of the shaft 10 being extended through the 50 plate 7 and having its outer end 11 projecting through the side of the hat crown and

provided with a suitable ornamental button 12 having a tubular shank 13 screwed thereon and adapted to be removed when it is desired to displace the fastener from the hat 60 crown.

14 indicates pins secured to the shaft 10 adjacent to the loops 6 and casing 8 respectively, and wound spirally around said shaft and also inclined from one another as clearly 65 shown in Fig. 1. The shaft 10 has an offset portion 15 between said pins 14 to permit rotation of the shaft without interfering with the arrangement of the hair of the wearer.

In use, the hat is secured on the head by rotating the shaft 10, the button 12 being used for this purpose, so that the points of the pins 14 are in a raised position. After placing the hat on the head, the button 12 70 is released and the spring 9 rotates the shaft carrying with it the pins 14, which, by engaging the hair will securely hold the hat in position on the head.

It will be understood that by having the 80 two pins 14 with their points inclined away from one another, as shown and described, all danger of scratching or injuring the scalp of the wearer, will be avoided, as they are far enough removed from one another 85 to prevent engaging the top of the head and the hat may be seated securely on the head without interfering with the operation of the pins. Furthermore, the offset portion 15 of the shaft 10 permits rotation of the shaft, 90 without in any manner interfering with the arrangement of the hair on the wearer's head, and also permits the hat to be seated securely on the head.

When it is desired to remove the fastener 95 from the hat, the button 12 is unscrewed from the end 11 of the shaft 10, the brackets 1 and 2 unfastened from the inside of the crown, and the shaft 10 may then be easily drawn from engagement with the side of 100 the crown without in any manner injuring the hat.

Having thus described our invention, what we claim is:—

1. In a hat fastener, shaft supporting 105 brackets adapted to be secured to the crown of a hat, one of the brackets provided with a laterally extending tubular casing, a shaft journaled in said brackets, a spring secured to said casing and shaft, and fastening 110 means secured to said shaft, said spring normally tending to rotate the shaft and

hold said fastening means in engaging position.

2. A hat fastener including a pair of shaft supporting brackets adapted to be mounted in the crown of a hat, one of said brackets being provided with an inwardly directed laterally extending tubular casing, a spiral spring mounted on said casing and having one end fixedly secured internally 5 thereof, a shaft journaled in said bracket, a plurality of resilient hair engaging members carried by said shaft, said spiral spring having its other terminal secured to the said shaft and disposed to normally hold the hair 10 engaging members in a position of positive engagement.

3. A hat fastener including a pair of supporting brackets adapted to be secured in the crown of a hat at diametrically opposite points thereof, an inwardly extending laterally directed tubular casing carried by 15

one of said brackets, a spiral spring arranged in said casing and having one terminal fixedly secured thereto, a shaft journaled in said brackets and disposed for rotation within the said tubular casing, the other end of said spiral spring being secured to said shaft, and a plurality of hair engaging members carried by the said shaft and arranged spirally with relation to the 20 longitudinal axis thereof, said hair engaging members being normally held in operative engagement by the action of the said spiral spring.

In testimony whereof we affix our signatures in presence of two witnesses.

WILLIAM OSCAR YANCEY.
CHARLES CAROLUS DU MESNIL.
